TYPEWRITING MACHINE

William A. Dobson, Wethersfield, Conn., assignor
to Underwood Elliott Fisher Company, New
York, N. Y., a corporation of Delaware

Application March 18, 1936, Serial No. 69,537

18 Claims. (Cl. 197—33)

This invention relates to typewriters and more particularly to devices for adjusting the reaction of key-levers for variations in finger-pressure of different operators. Operators vary in 5 the degree of lightness or heaviness of touch, and in manifolding employ a different touch than is the case with the usual typewriting. To meet the several conditions of use, it is desirable to provide a construction having strong, simple and 10 precise parts, a quick and facile manual adjustment of the key-lever yieldability for several conditions, accessible at a convenient point outside the typewriter, and an indicator that shows the operator the exact adjustment.

15 A feature of the invention is the provision of a universal bar and a spring for returning the bar to normalcy after depression by a key-lever, coupled with a second adjustable spring which becomes effective for co-operative action with the 20 first spring after a predetermined depression of a key-lever, whereby the keys may be adjusted for operators of very light touch and for operators with a heavier touch.

Another feature of the invention is the provision 25 of a simple, low-cost, durable, and serviceable construction for the purpose of permitting the adjustment of the resilient yieldability of the keys to the differing touch of various operators that may be installed in an Underwood portable 30 typewriter of present structure with few and simple manufacturing adjustments.

Another feature of the invention is the provision 35 of a manual device for adjusting the key-touch to several conditions accessible exteriorly of the typewriter, and the provision of an index and scale visible exteriorly of the typewriter indicating each of the several adjustments.

Another feature of the invention is the provision 40 of a second spring connected with the universal bar which has a lost-motion connection, whereby it becomes effective only after the universal bar has been depressed an amount equal to the lost motion. This construction permits of an adjustment for a very light touch. To prevent 45 torsion or skewing on the universal bar two springs may be provided, one on each end, each having the same tension and the same lost-motion connection. The rigidity of the universal bar and its resistance to bending, as well as keeping 50 the bar relatively light and small, are essential to compact and low-cost manufacture. Any bending or yielding of the universal bar may easily affect the accuracy of operation of the ribbon-vibrating mechanism, or of the escapement. 55 The provision of arms slidably mounted, in

brackets, in the same direction as the paths of expansion and contraction of the springs, eliminates the need for extra space, and results in a compact construction easily positioned within present existing vacancies between parts in an 5 Underwood portable typewriter. The provision of a transverse rotatable shaft permits of the mounting of eccentric cams on the shaft, one beneath each of the slidable arms, whereby the rotation of the shaft raises and lowers the arms 10 equally and simultaneously, and so therefore increases and decreases the tension of the secondary pair of springs equally and uniformly to concomitantly vary the yieldable resistance of the universal bar and consequently the yieldability 15 of the keys, which permits key-adjustment for varying touch and also permits adjustment for manifolding. The index shows any selected adjustment, and there is provided further a yieldable stop which holds the shaft at any rotational 20 adjustment selected.

Another feature of the invention is the provision of a simple, low-cost construction whereby the key-touch may be rendered more agreeable and the operation of the machine less fatiguing 25 to the operator, and also whereby the action of the keys may be varied from exceedingly stiff and resisting to very elastic.

Other features and advantages will hereinafter appear.

30 In the accompanying drawing,

Figure 1 is a perspective view with parts broken away and parts in section.

Figure 2 is a side elevation partly in section and with parts broken away, also showing a lever connection for operating the ribbon-feed mechanism.

Figure 3 is a fragmentary elevation, partly in section, of a key-lever overlying the edge of a universal bar, and spring suspension of the universal bar on an adjustable arm.

Figure 4 is a fragmentary sectional elevation, partly in section, showing the left end of the adjustment-control rod and allied parts.

45 Figure 5 is an elevation of the dial.

Figure 6 is a view similar to that of Figure 3, but showing a modification.

Certain parts of an Underwood portable typewriter which intimately co-operate with the improvements disclosed herein are shown in the 50 drawing, comprising a frame 1 covered by a mask 2, and key-levers 9 having recesses 10 on the upper surfaces at the rear ends pivoted on the lower edge of depending cross-flange 11. A lock-plate 12 is fastened to the flange 11 and locks the key- 55

- levers 9 against displacement. A cross-piece 13 in the frame supports a row of upwardly-projecting screws 14 which carry at their upper ends cylindrical pins 15. Mounted on each pin is a coil-spring 16 which is held under each key-lever 9 by a pointed downward projection 17. These tension-springs 16 tend to hold the key-levers 9 in the upper or normal position. The lower ends of the screws 14 are each provided with two opposed flat faces 18, the rear face being engaged and locked yieldably against turning by the edge of a loop-spring 19, which is held by screws 20, or other suitable means on the under surface of the cross-piece 13.
- 15 A link-arm 24 is pivoted on a cross-rod 25 and has a pin-and-slot connection 26 with the key-lever 9. A link 27 is pivoted on the rear end of the link-arm 24, and is also pivoted to the bottom of a type-bar 28, type-bar 28 being pivoted 20 on a type-bar rod 29.
- 15 A universal escapement-bar 30 is shown in Figure 2 in the inoperative position of a type-bar 28. Each type-bar 28 is provided with type 31. In the inoperative position each type-bar 28 recedes on a stop 32, and the upward movement of the key-levers 9 is checked by a stop 33. A platen 34 is indicated in Figure 1.
- 15 A universal bar 35 having side arms 36 is pivotally mounted for upward and downward movement on a cross-rod 37, which also acts as a rock-shaft, and is mounted at the opposite ends in brackets 38 suitably fastened to a depending flange of the cross-piece 13.
- Referring to Figure 2, an arm 39 is fast on 35 the cross-rod 37, and has a pivotal connection 40 with the rear end of a horizontal arm 41, which carries at the forward end a tooth 42 which resiliently engages a ribbon ratchet-wheel 43 mounted on a ribbon-shaft 22. The backward 40 turning of the ribbon ratchet-wheel 43 is prevented by a pawl 44 which oscillates on a pin 21, the rear extension of the pawl 44 being tied to the forward part of the arm 42 by means of a spring 45.
- 45 A bracket 46 centrally mounted on the cross-piece 13 supports at its forward end a tension-spring 47, which is pinned centrally on the upper side of the universal bar 35. A pair of similar coil-springs 48 are fastened at their lower ends 50 near the universal bar but on the side arms 36, each coil-spring terminating at its upper end in a loop 49, which lies within but above the bottom of a V-slot 50, which may also be designated as a "lost-motion" slot formed on the upper side 55 of a rearwardly-extending arm 23 supported by an inclined slide 51, which is mounted slidably in slotted arms 52 in a bracket 53, which is secured by rivets 54 on the inside wall of the frame 1. It will be understood that there is a coil or 60 tension spring 48 on or near each end of the universal bar 35 supported by these lost-motion slots 50 provided in the arms 51 which are slidably mounted in the brackets 53 on the frame, the parts being symmetrical. Two eccentric 65 cams 55 are mounted on a shaft 56 which is journaled in the frame of the machine, one cam being mounted near each end of the shaft 56, and the cams being symmetrically positioned. A set-screw 57, shown in Figure 3, locks each cam 70 55 in its fixed position on the shaft 56. A stop 58 on each cam 55 limits the movement of pointer 61 to the right of numeral 1. These cams 55 engage the lower ends of the inclined slides 51 and form stops or rests for the slides to hold 75 them against their downward movement.

A knurled thumb-piece 59 or manipulative means is mounted on a left extremity of the shaft 56 outside the frame 7 and the mask 8, and is locked against rotation on the shaft 56 by a set-screw 60 positioned between the frame 5 7 and the mask 8, as shown in Figure 4. Mounted on the knurl 59 is the pointer 61, which indicates the index numerals 1, 2, 3, 4, 5 and 6, according to the rotary position of the shaft 56. The pointer 61 is near the index numeral 1, as 10 shown in Figure 5, which is also the position of the cams 55 and the slide-arms 51, or, in other words, the initial position of the tension-springs 48, as shown in Figures 1, 3 and 6. The neck of the knurl 59 is provided with horizontal grooves 15 63 which are engaged by a horizontal ridge 64 which is formed in the lower end of a flat spring 65, which is fastened in the space between the frame 7 and the mask 8 by set-screws 66 on the outer wall of the frame 7. A stop 67 is set in the 20 outer wall of the frame 7 near the horizontal grooves 63 in a position to engage the set-screw 66, thereby providing a stop against the turning of the knurl 59 beyond the position of final adjustment at which the pointer 61 would be opposite the numeral 6 shown in Figure 5.

Referring to Figure 3, there are shown above the cam 55 dotted lines 68, 69, 70, 71 and 72 which indicate the positions of the bottom of the slides 51, when the index pointer 61 is set respectively by the numerals 2, 3, 4, 5 and 6. Reference is made to Figure 6 for a modification in which two supplemental V-slots are provided on the arm 23, one shorter V-slot 73 on the right of the V-slot 50 as shown, and a V-slot 74 at 35 the left of the V-slot 50 as shown. A tie-rod 75 connects the rear bottom extremities of the frame 7.

In Figure 3 it will be noted that the height of the loop 49 over the bottom of the groove 50, 40 or the downward motion of the spring 48, or its "lost motion", is only a fraction of the total downward movement of the universal bar 35, or the distance between the full-line position and the dotted-line position of the universal bar. 45 Throughout the initial part of the down stroke of the universal bar 35, or the part of the down stroke that is equivalent to the distance that the loop 49 is initially above the bottom of the V-slot 50, the only tension that is effective on the 50 universal bar is that of the centrally positioned light coil-spring 47. During the last part of the down stroke of the universal bar 35, the pair of coil-springs 48 are effective, continuously increasing their tension up to the point that the 55 down stroke of the key-lever 9 culminates in the contact of the type 31 with the platen 34. Instantly upon removing the finger from the key-lever 9, the three springs 47 and 48, 68 are effective under their greatest tension to lift the 60 key-levers 9 and to return the type-bar 28 to the segmental rest 32, the two springs 48, 49 being equally and uniformly effective on the extremities of the universal bar 35, and the coil-spring 47 being centrally effective, whereby uniform upward tension is exerted on the universal bar 35. The Figure 3 position is that of the Figure 5 position in which pointer 61 is at index numeral 1.

Let it be assumed that the knob 59 is turned 70 from index numeral 1 to index numeral 2, and that simultaneously the cams 55 are rotated to the left, thereby lifting the slides 51 a distance that is equal to the difference between the top of the cams 55 and the horizontal line 68, where 75

they are set; then this difference in the height of the slides 51 above the cams 55 may be sufficient to overcome the height of the loops 49 above the bottom of the grooves 59, so that, upon the inauguration of the down stroke of a key-lever forthwith, all three coil-springs 47, 48, 48 exert upward tension on the universal bar 35, and the tension at the end of the down stroke is greater than in the case of the setting shown in Figures 3 and 5.

Similarly the tension is increased by turning the index pointer 61 to the numeral "3", at which setting the bottom of the slides 51 is at the line 69 in Figure 3, and so index numerals 4, 5 and 6 correspond respectively to bottom positions of the slides 51 at lines 10, 11 and 12.

The modification shown in Figure 6 provides two additional "lost motion" V-slots, V-slot 73 of less depth than V-slot 50, and at the right thereof, which may be used for the original setting of the loop 49 where slightly more initial tension is desired, and V-slot 74 of somewhat greater depth permitting more lost motion to the pair of springs 48, thereby providing for the condition of a lighter touch than that shown in Figure 3. In the case of an initial setting in V-slot 73, it will be understood the five other settings indicated by index numerals, 2, 3, 4, 5 and 6 will be proportionally of greater tension, each setting than the corresponding setting in the construction shown in Figure 3, and likewise in the case of an initial setting in V-slot 74 the five other settings will be of proportionally less tension.

It will be further understood that the degree of variation in the tensions procured at the various settings may be decreased by increasing the number of teeth 63 that intercept the horizontal ridge 64 on the lock-spring 65, or by any other desired construction known in the art. Such modifications are not shown.

Variations may be resorted to within the scope of the invention, and portions of the improvements may be used without others.

Having thus described my invention, I claim:

1. A typewriter comprising, in combination, key-levers, a universal bar extending across and beneath said key-levers and compressible by said key-levers, a spring centrally connected with said bar and operable to resist the depression of said bar and to return the bar to normalcy, a pair of springs which become effective simultaneously, whereby skewing or warping of the universal bar is prevented, after a predetermined movement of depression of a key-lever, and means for simultaneously adjusting said pair of springs to vary their tension.

2. A typewriter comprising, in combination, key-levers, a universal bar extending across and beneath said key-levers and compressible by said key-levers, a spring centrally connected with said bar and operable to resist the depression of said bar and to return the bar to normalcy, a pair of springs which become effective simultaneously, whereby skewing or warping of the universal bar is prevented, after a predetermined movement of depression of a key-lever, means for simultaneously adjusting said pair of springs to vary their tension, and an index for indicating the adjustment of said pair of springs.

3. A typewriter comprising, in combination, key-levers, a universal bar extending across and beneath said key-levers and compressible by said key-levers, a spring connected with said bar and operable to resist the depression of said bar and

to return the bar to normalcy, a second spring which becomes effective for co-operative action with the first spring after a predetermined movement of depression of a key-lever, an arm having a lost-motion support for said second spring, and means for moving said arm to adjust the tension of said second spring.

4. A typewriter comprising, in combination, key-levers, a universal bar extending across and beneath said key-levers and compressible by said key-levers, a spring connected with said bar and operable to resist the depression of said bar and to return the bar to normalcy, a pair of springs, one fastened on each end of the universal bar, which become effective simultaneously, whereby skewing or warping of the universal bar is prevented, after a predetermined movement of depression of a key-lever, and means for simultaneously adjusting said pair of springs to vary their tension.

5. A typewriter comprising, in combination, key-levers, a universal bar extending across and beneath said key-levers and compressible by said key-levers, a spring connected with said bar and operable to resist the depression of said bar and to return the bar to normalcy, a second spring which becomes effective for co-operative action with the first spring after a predetermined movement of depression of a key-lever, an arm having a lost-motion support for said second spring, and means, comprising a cam, for moving said arm to adjust the tension of said second spring.

6. A typewriter comprising, in combination, key-levers, a universal bar extending across and beneath said key-levers and compressible by said key-levers, a spring connected with said bar and operable to resist the depression of said bar and to return the bar to normalcy, a second spring which becomes effective for co-operative action with the first spring after a predetermined movement of depression of a key-lever, an arm for supporting said second spring, a lost-motion engagement between said arm and said second spring, and means for moving said arm to adjust the tension of said second spring.

7. A typewriter comprising, in combination, key-levers, a universal bar extending across and beneath said key-levers and compressible by said key-levers, a main spring connected with said bar and operable to resist the depression of said bar and to tend to return the bar to normalcy, a pair of returning springs auxiliary to said main spring, one fastened to each end of the universal bar, a movable arm for supporting each auxiliary spring, a shaft rotatably mounted and supporting cams, one near each arm, manually-operable means connected with said shaft and accessible from outside the typewriter for turning said cams to adjust said pair of auxiliary springs, an indicator mounted on said shaft, and yieldable means for holding said cams in a plurality of positions rotatably.

8. A typewriter comprising, in combination, key-levers, a universal bar extending across and beneath said key-levers and compressible by said key-levers, a main spring connected with said bar and operable to resist the depression of said bar and tending to return the bar to normalcy, an auxiliary spring fastened at one end of the universal bar, a movable arm for supporting said auxiliary spring, a shaft rotatably mounted and supporting a cam which engages said movable arm, manually-operable means connected with said shaft and accessible from outside the type-writer for turning said cam to adjust said

auxiliary spring, an indicator for indicating the position of said cam, and yieldable means for holding the cam in a plurality of rotative adjustments.

- 5 9. A typewriter comprising, in combination, key-levers, a universal bar extending across and beneath said key-levers and depressible by said key-levers, a spring connected with said bar and operable to resist the depression of said bar and 10 to return the bar to normalcy, an auxiliary spring fastened at one end of the universal bar, a movable arm for supporting said auxiliary spring, a bracket for slidably supporting said arm, a shaft rotatably mounted and supporting a cam 15 which engages said movable arm, manually-operable means connected with said shaft and accessible from outside the typewriter for turning said cam to adjust said auxiliary spring, an indicator for indicating the position of said cam, and 20 yieldable means for holding the cam in a plurality of rotative adjustments.

10. A typewriter comprising, in combination, key-levers, a universal bar extending across and beneath said key-levers and depressible by said key-levers, a spring connected with said bar and operable to resist the depression of said bar and tending to return the bar to normalcy, an auxiliary spring fastened at one end of the universal bar, a movable arm for supporting said auxiliary 25 spring, a bracket for slidably supporting said arm, a shaft rotatably mounted and supporting a cam which engages an end of said movable arm, manually-operable means connected with said shaft and accessible from outside the typewriter for turning 30 said cam to adjust said auxiliary spring, an indicator for indicating the position of said cam, and yieldable means for holding the cam in a plurality of rotative adjustments.

11. A typewriter comprising, in combination, 40 key-levers, a universal bar extending across and beneath said key-levers, a main spring centrally connected with said universal bar and operable to resist the depression of said bar and tending to return the bar to normalcy, a pair 45 of auxiliary springs, one fastened at each end of the universal bar, movable arms for supporting said auxiliary springs, brackets for slidably supporting said arms, a shaft rotatably mounted and supporting cams which engage the ends of said movable arms, manually-operable means 50 connected with said shaft and accessible from outside the typewriter for turning said cams to adjust said pair of auxiliary springs simultaneously, an index to show the adjustment of 55 said pair of auxiliary springs, and a plurality of radially disposed stops on said shaft, and resilient means engageable with said stops whereby the tension of said pair of auxiliary springs is yieldably maintained in any adjusted position.

12. A typewriter comprising, in combination, 60 key-levers, a universal bar extending across and beneath said key-levers, a main spring centrally connected with said universal bar and operable to resist the depression of said bar and to return the bar to normalcy, a pair of auxiliary springs, one fastened at each end of the universal bar, movable arms for supporting said auxiliary springs, brackets for slidably supporting said arms, a shaft rotatably mounted and 65 supporting cams which engage the ends of said movable arms, manually-operable means connected with said shaft and accessible from outside the typewriter for turning said cams to adjust said pair of auxiliary springs simultaneously, an index to show the adjustment of said 70

pair of auxiliary springs, a plurality of radially-disposed and horizontally-grooved stops on said shaft, and a stop spring having a ridge engageable with said stops, whereby the tension of said pair of auxiliary springs is yieldably maintained in any adjusted position. 5

13. In a typewriter having a system of key-levers, in combination, a universal bar mounted for actuation by each of the key-levers, a spring connected to said bar to yieldably resist movement thereof by the key-levers, a pair of auxiliary springs connected to said bar to co-operate with the first spring in yieldably resisting the movement of said bar, a separate movable mount for each auxiliary spring, and manually settable 15 means for moving said mounts so as to adjust the tension of each auxiliary spring simultaneously. 10

14. A typewriter comprising, in combination, key-levers, a universal bar extending across and beneath said key-levers and depressible by said key-levers, a spring connected to said bar and operable to resist the depression of said bar and to return the bar to normalcy, a second spring connected to said bar and which becomes effective 20 for co-operative action with the first spring after a predetermined movement of depression of a key-lever, an arm for supporting said second spring, and a rotatable cam for moving said arm whereby to adjust the tension of said 25 second spring.

15. A typewriter comprising, in combination, key-levers, a universal bar extending across and beneath said key-levers and depressible by said key-levers, a spring connected to said bar and operable to resist the depression of said bar and to return the bar to normalcy, a second spring connected to said bar, which becomes effective for 30 co-operative action with the first spring after a predetermined movement of depression of a key-lever, an arm for supporting said second spring, means for moving said arm, comprising a rotatable cam, to adjust the tension of said second spring, and means for holding the cam in the various positions of adjustment. 35

16. A typewriter comprising, in combination, key-levers, a universal bar extending across and beneath said key-levers and depressible by said key-levers, a spring connected to said bar and operable to resist the depression of said bar and 40 to return the bar to normalcy, a second spring connected to said bar, which becomes effective for co-operative action with the first spring after a predetermined movement of depression of a key-lever, an arm for supporting said second spring, means for moving said arm, comprising a rotatable cam, to adjust the tension of said 45 second spring, and yieldable means for holding the cam in various positions of adjustment.

17. A typewriter comprising, in combination, 50 key actuated type actions, a universal bar movable by any of said type actions, a spring connected to said bar and effective at the operation of any of said type actions to resist the movement of said bar and to return the bar to normalcy 55 together with any one of said type actions, an auxiliary spring having connection at one end to said bar, a support having connection to the other end of said auxiliary spring, one of said connections being adapted to permit an initial 60 limited motion of said bar without resistance of said auxiliary spring, whereby the latter is adapted to cooperate with the first spring after a predetermined movement of depression of any type action key, and means for adjusting said 65 70

auxiliary-spring support for adjusting said limited motion of said bar to vary the point in the depression of said bar at which said auxiliary spring becomes effective.

5 18. A typewriter comprising, in combination, a casing, key actuated type actions, a key-touch controlling universal bar movable by said type actions, a spring connected to said bar and effective at the operation of any of said type actions 10 to resist the movement of said bar and to return said bar to normalcy together with any one of said type actions, an auxiliary spring having

connection at one end to said bar, shiftable means having connection to the other end of said auxiliary spring, one of said connection being adapted to permit initial limited motion of said bar without resistance of said auxiliary spring, and manipulative means on the outside of the casing, adapted to adjust said shiftable means to different positions for reducing said limited motion and successively adjusting the tension of said auxiliary spring to enable it to vary the 10 resistance of all of the type action keys uniformly.

WILLIAM A. DOBSON.
